UNITED STATES PATENT OFFICE.

JOSEPH H. LAWTON, OF MIDDLE FALLS, NEW YORK.

INVALID ATTACHMENT FOR BEDS.

SPECIFICATION forming part of Letters Patent No. 373,668, dated November 22, 1887.

Application filed June 6, 1887. Serial No. 240,471. (No model.)

To all whom it may concern:

Be it known that I, JOSEPH H. LAWTON, of Middle Falls, in the county of Washington and State of New York, have invented certain new and useful Improvements in Invalid Attachments for Beds; and I do hereby declare the following to be a full, clear, and exact description of the invention, such as will enable others skilled in the art to which it pertains to make and use it, reference being had to the accompanying drawings, which form part of this specification.

My invention relates to an improvement in invalid attachments for beds; and it consists in the combination of a crane, an operating-shaft around which the belts, wires, or chains are wrapped, one or more levers which are pivoted upon the crane, a frame which is attached to the outer ends of the levers, and a stretcher of any kind, which is connected to the frame, and upon which the invalid lies while being moved, as will be more fully described hereinafter.

The object of my invention is to provide an elevating apparatus, which is to be used in connection with beds, so that invalids can be raised above the bed and then swung around from it in any desired direction without having to lift them by hand.

Figure 1 is a side elevation of an apparatus embodying my invention. Fig. 2 is a plan view of the same.

A represents a suitable standard, which has its lower end secured to the floor in any suitable manner, and which is supported at its upper ends by one or more rods or braces, B, which extend outward and are fastened to the wall. Secured to this standard are suitable bearings, C, in between which the crane D is held. Journaled in this crane is the operating-shaft E, having secured to one end the wheel, crank, or handle F, by means of which it is operated. Used in connection with this shaft will be a pawl and ratchet, a, for the purpose of holding the shaft in any desired position. This shaft forms a drum, around which the belts C are wound at their inner ends. The outer ends of the belts, wires, or chains are secured to the inner ends of the levers H, which are pivoted upon the outer end of the crane. These levers H will be of any desired length and are prefer-

ably curved or bent at their ends, as shown, so as to give a greater amount of vertical movement to the frame I, which is attached to them by means of the bands, wires, or chains J, than could be done if the levers were perfectly straight.

Heretofore pulleys have been used at the outer ends of the cranes for the lifting ropes or cords to pass over. When only ropes or cords are used but comparatively little vertical movement can be given to the frame I; but where the levers H are used the frame can be moved laterally, as shown by dotted lines, and given a much greater amount of motion than can be done where the usual pulley is used. The levers H also give additional leverage, and thus enable women to move heavy persons with greater ease than they can do where no levers are used.

The frame I can be constructed as hereshown or in any other way that may be preferred, and to this frame is attached, by any suitable fastenings the canvas stretcher L, upon which the patient rests. This stretcher is preferably provided with a pillow at one end, as shown. This stretcher will preferably be placed over the top of the bed, and over it a sheet will be placed. The patient in resting upon this canvas can at any time have it attached to the frame I, and then the patient can be raised upward above the bed and swung around to some other portion of the room, for the purpose of being placed upon a chair, or be held while the bed is being made up.

By means of an apparatus constructed as here shown and described a patient can be raised and lowered from the bed at any time by the expenditure of but very little power, owing to the compound leverage of the levers and drum, and thus all heavy lifting is entirely avoided. It also enables a patient to be transferred from the bed to a chair with but very little effort upon the part of the patient or the nurse.

Having thus described my invention, I claim—

1. The combination of the standard, the crane connected thereto, the operating-shaft provided with a wheel, crank, or lever, the belts or chains, which are wrapped upon the shaft, the pivoted levers connected to the crane,

the belts which connect the frame to the outer ends of the levers, the frame, and the stretcher which is connected to the frame, substantially as shown and described.

5 2. The combination of the crane, pivoted levers connected thereto, an invalid-bed attachment flexibly secured to the levers, a windlass or drum on the crane for operating the levers, and a flexible connection between the

inner ends of the levers and the windlass, substantially as set forth.

In testimony whereof I affix my signature in presence of two witnesses.

JOSEPH H. LAWTON.
